UNITED STATES PATENT OFFICE

2,468,010

ELECTRIC VAPORIZER

Samuel Duberstein, Brooklyn, N. Y., assignor to
American Sundries Company, Inc., a corpora-
tion of New York

Application April 11, 1946, Serial No. 661,245

7 Claims. (CL. 219—40)

1

This invention relates to electric vaporizers having liquid spraying or diffusing means operated therefrom. Such devices are coming into common use not only as insecticides, but as medicinal aids for colds, croup, asthma and other respiratory troubles.

More particularly, my invention is an improvement in the type of electric vaporizer shown in the prior patent to applicant and Nicholas Lawner, No. 1,933,245, dated October 31, 1933. In this type of vaporizer the steam is generated by heating the water in a closed container by passing alternating current through the water between spaced electrodes. It is usual to make the container of an insulating material, such as glass, to avoid shock.

One object of the present invention is to avoid injury to the user in case of breakage or explosion of the glass container, or in case the detachable top became damaged and blew off.

Another object of the present invention is to improve upon the combined filling plug and safety or relief valve employed in such vaporizers, whereby a more sturdy construction and larger filling opening are secured and ready adjustment of the blow-off pressure is secured.

A still further object is to so construct the insecticide or medicinal container that the liquid is heated materially during operation by extended contact or proximity with the metal housing of the water container.

Referring to the drawings disclosing a preferred form of my invention,

Fig. 1 is a vertical section of my improved vaporizer;

Fig. 2 is a plan view partly in transverse section of the same;

Fig. 3 is an enlarged sectional view of my improved safety valve; and

Fig. 4 is a transverse section on line 4—4 in Fig. 3.

As shown in the drawing, the water jar or container 1 may be made of glass or other non-conductor. It has an open top 2, the bottom of the jar resting on a detachable bottom plate 3 of the outer housing 4, both the plate and housing being preferably made of metal or other strong material. The housing 4 together with bottom and top plates 3 and 6 encloses the jar at all points except for one or two slots 5 in the side thereof, so that the water level may be observed.

Detachable top plate 6 is in use clamped between the top of the jar 2 and the underside of a circular inwardly projecting flange 7 on top of

the housing 4. In assembly, the top plate 6 is first inserted through the hole in the bottom of the housing, and the jar is also put in from the bottom until its top is brought against the rubber washer 8 extending around the edge of the top plate 6. Bottom plate 3 is then put in place and securely fastened by means such as set screws 9. Between the bottom of the jar and plate 3 there may be provided a resilient pad 10 of rubber, felt or the like. The design is such that the top of the jar is held firmly against the washer on the top plate when the parts are in place, so that no steam can escape.

By thus completely surrounding the glass jar by metal, the likelihood of injury to the user by breakage or explosion of the jar is greatly lessened. Also, the danger of blow-off of the top due to damaged threads, as is the case where the top is screwed on the jar as shown in the afore-
20 said patent, is practically eliminated.

On the top plate 6 are mounted the two prongs 11, 11' through which current is introduced to the spaced electrodes 12, 12' secured to the under side of said plate and by which current is led into the water to heat the same by passage of the current through the water. These electrodes preferably have a substantial area so that passage of a substantial amount of current is secured with the presence of a minimum amount of saline impurities in the water.

Also threaded in the top is my improved combined safety valve 13 and filling plug. This valve is shown as having the usual central stem 14 and bottom nut or abutment 15 and spiral compression spring 16. However, instead of securing adjustment of the stiffness of the spring by adjusting the bottom nut thereon as is the usual practice and which requires removal of the valve, I provide an extra threaded sleeve 17 at the top of the device, which sleeve is slidably but non-rotatably mounted on the stem 14, the stem being shown as having enlarged area with flattened sides 18 near the top thereof. At its top there is secured to said stem a top piece 20 having a knurled flange 21. The bottom of member 20 seats on a circular valve seat 40 on the top of boss 41 on plate 6. Normally the sleeve 17 is pressed against collar 46 within the cap by spring 16.

When in use, the valve structure is screwed into place in the threaded filling opening 19 in the top of the plate 6 until the knurled top 20 is seated. Further turning of the member 20 will then screw the sleeve 17 downwardly into the opening, thus drawing it away from the collar

46, thus increasing the compression of the spring and increasing the blow-off pressure of the valve.

The opening or valve seat for my relief valve also furnishes a convenient means for filling the jar which is of ample area as compared to prior devices of this nature. My valve has the further advantage that the knurled top 20 by which the valve is unscrewed does not contact the metal top except around its seat and hence becomes less hot and more easy to handle than the design of 10 the aforesaid prior patent.

The steam is discharged from the jar through a metal spout 22 which may be screwed into the side of a boss 41 on cap 6 and which has a small bore 23 terminating in a nozzle 24. In operation, 15 a jet of steam is projected by the nozzle past the tip of a pipe 25 which projects downwardly into the container 26 for the insecticide or medicament. Container 26 is shown as a metal jar, with a concave side wall 43 which fits closely the 20 outside of the metal housing 4. This construction not only helps support the container, but to heat the liquid therein during operation. The metal container is shown as hung on the housing 4 by means of a bracket 27 having a vertical slot 28 therein which is slipped over a set screw 29 fixed on the side wall of container 4. The housing 4 is also shown as provided with a handle 30 of insulating material clamped between brackets 31 and 32 extending from frame 4. The handle 30 may be made hollow to receive the insulated wire carrying current to the electric plug (not shown) which detachably engages the prongs 11.

It will be understood that in operation the steam jet discharged from nozzle 24 draws liquid up through pipe 25 by an aspirator action and discharges and diffuses it into the air as a mist with the steam. My vaporizer is very effective as a treatment for respiratory diseases, as well as an insecticide.

Since many changes could be made in the above construction and many widely different embodiments could be made without departing from the scope thereof, it is intended that all matter contained in the above description and shown in the accompanying drawings shall be interpreted as illustrative and not in a limiting sense.

What is claimed is:

1. In an electric vaporizer, a liquid container having an open top, and a closure or top plate therefor, an outer housing for said container having a detachable bottom plate and a top flange, means for clamping the bottom plate against the container to hold it tightly against its top plate and the flange of said housing, and a steam discharge nozzle also in said top plate.

2. In an electric vaporizer, a liquid container having an open top, an outer protective housing therefor substantially completely surrounding said container, said housing having a detachable bottom plate and a top plate having secured thereto a steam discharge nozzle and heating electrodes, whereby upon removing the bottom plate and jar the top plate and electrodes remain within the outer housing.

3. An electric vaporizer comprising a liquid receptacle having an open top, a closure or top plate therefor, an outer housing for said receptacle having an inwardly projecting flange at its top, and an open bottom through which said receptacle is thrust in assembling, a steam nozzle member on the outside of said plate, an electric

heating unit suspended from the inside of said plate and adapted to project downwardly into said receptacle, said plate having terminals thereon which project through it for engagement with an electric plug, a detachable bottom plate or closure for said housing adapted to clamp said top plate and said receptacle against said flange, a second receptacle external said housing and a tube attached adjacent its upper end to said nozzle member with its lower end adapted to be submerged in the liquid in said second receptacle.

4. An electric vaporizer as claimed in claim 3 in which said second liquid receptacle is of metal and has a concave inner wall adapted to closely fit the outer housing.

5. In an electric vaporizer or the like, a combined safety valve and filling plug comprising, a stem having a cap forming a valve closure adjacent the top thereof and an abutment below said top, a threaded sleeve slidably but non-rotatably mounted on said stem between said cap and abutment, and adapted to be screwed into a threaded opening in the vaporizer by turning said cap, said opening having a valve seat thereon engaged by said cap as the valve is screwed into place, and a compression spring on said stem between said abutment and said sleeve yieldably holding said cap on its valve seat.

30 6. In an electric vaporizer or the like, a combined safety valve and filling plug comprising a stem having a fixed abutment adjacent the bottom thereof and a cap forming a valve closure secured to the top thereof, a threaded sleeve slidably but non-rotatably mounted on said stem under said cap and adapted to be screwed into a threaded opening in the vaporizer by turning said cap, said opening having a valve seat thereon engaged by said cap as the valve is screwed 40 into place.

7. In an electric vaporizer, a liquid container of non-conducting relatively fragile material, and having an open top, an outer metallic housing therefor adapted to substantially completely enclose said container, said housing including an outwardly removable bottom plate adapted to fit against the outer periphery of a bottom flange around an opening in the bottom of the housing, and a top plate which may be removed only 45 through the open bottom of said container and which is adapted to fit against the inner periphery of a top flange around an opening in the top of the housing, and means for detachably securing the bottom plate to the bottom of the 50 housing thereby pressing the top of the jar against the top plate, and the top plate against said top flange, and a steam discharge outlet in 55 said top plate.

SAMUEL DUBERSTEIN.
